PROTECTING DEVICE FOR SHIPS

Say Louis Lee, New York, N. Y.

Application May 26, 1944, Serial No. 537,380

2 Claims. (Cl. 114—240)

My invention relates to a new and improved protecting device for ships. The principal object thereof is to provide a novel protecting contrivance along the opposite sides of the hull of a ship, so as to effectively prevent injury to the hull by torpedoes, projectiles, mines or by collision.

Another object of my invention is to provide improved means for protecting and reinforcing the sides of a ship, which means can be moved into their operative and inoperative positions by any suitable source of power.

Another object of my invention is to provide a protector device along the opposite sides of the hull of a ship, the said device being movable vertically to compensate for tides, etc., and also being movable away from the hull to its extended or operative position, and also being movable toward the hull to its collapsed or inoperative position in abutting relation to the sides of the ship.

Still another object of my invention is to provide a new and improved protecting device which can be installed and incorporated into any standard ship or boat of any size or type, without the necessity of changing or altering the structure of such ship or boat. Numerous additional objects of my invention will be set forth in the annexed description and drawings, which illustrate a preferred embodiment thereof.

Fig. 1 is a side elevational view of a ship equipped with the improved protecting device, the said device being shown in collapsed position or brought in against the hull.

Fig. 2 is a top plan view of the ship and the protecting means shown in Fig. 1.

Fig. 3 is an enlarged fragmentary side elevation of the ship and the protecting device, the said device being shown in the extended or operative position.

Fig. 4 is a sectional view on the line 4—4 of Fig. 3, a fragmentary portion of the ship being shown in top plan.

Referring to the drawings in detail, the reference letters A indicate the ship, H the hull thereof, B the bow and S the stern.

The improved protecting device includes the side protecting devices D and DD, and the means for controlling the movements thereof.

Contrivances D and DD are identical in construction and operation and each of said devices is arranged and movably positioned along the opposite sides of hull H.

Each of devices D and DD includes a plurality of U-shaped arms 10 which are movably mounted

on vertical bars 11 by looping or bending the free ends of the horizontal portions of said arms 10 about said bars 11. In this manner, arms 10 are movable vertically on bars 11 and said arms 10 are also swingably movable to and away from hull H. Each bar 11 is held in its vertical position by a coaxially aligned pair of rings or staples 12 which are driven into or secured to the opposite sides of hull H as shown in Figs. 2 and 4; each of said rings 12 being located adjacent the vertical end portions of each of said bars 11. To prevent bars 11 from slipping through rings 12, the top end portion of each of said bars is bent at an angle with respect to the vertical portion thereof, to form the lateral horizontal terminal 13 and the bottom end of said bars is provided with the nut N, the top face of said nut abutting the bottom face of lower ring 12.

Each U-shaped arm 10 is identical in construction and configuration. It will be noted that the free ends of the horizontal portions of these arms after being looped about bar 11 are provided with the integral terminal projections 14. These projections 14 act as stops which limit the swinging movement of arms 10 away from hull H. In the operative or extended position, projections 14 are parallel to hull H and in the collapsed or inoperative position said stops are perpendicular to the hull. This is clearly illustrated in Figs. 2 and 4. The function and operation of these projections 14 will be hereinafter explained more fully.

It will be noted from Figs. 1 and 2, that I include in my protective device five U-shaped arms 10 on each side of hull H. However, I do not wish to be limited to any particular number as this may be varied as desired depending on the size of the ship.

As shown in Fig. 1, the upper horizontal portion of each arm 10 has a chain or cable 15 secured to it, the opposite end of said chain being secured to the railing 16 on the deck of ship A, one of said railings being provided on each side of the ship. These chains 15 are employed whenever it is desired to hold arms 10 in raised vertical position to compensate for tides, varying water levels, etc.

Running parallel cables 17 connect all of the U-shaped arms 10 on each side of hull H so that said arms will move in unison. This is accomplished by connecting said cables 17 to said arms adjacent the ends of the vertical portions thereof in any suitable manner, as for example, by passing the cables around the same. Secured to cables 17 intermediate arms 10 are the vertical

or upright deflector bars 18. Said bars 18 may be of any desired width and any number thereof may be secured to cables 17 intermediate each U-shaped arm 10.

Referring now to the bow portion of the ship and particularly to Figs. 1 and 2 of the drawings, the ends of upper and lower cables 17 on each side of the ship are brought together and pass through rings or staples 19 secured on opposite sides of bow B. Each pair of cables 17 from both sides of the ship then pass on to the deck of ship and all four cables are brought together and pass through ring or staple 23 secured to the deck adjacent bow B.

Referring now to the stern portion of the ship and also to Figs. 1 and 2 of the drawings, the ends of upper and lower cables 17 on each side of the ship are brought together and pass through rings or staples 20 secured on opposite sides of stern S. Each pair of cables from both sides of the ship pass on to the deck of the ship and all four cables are brought together and pass under ring 24 secured to the deck adjacent stern S.

Mounted on each end of the ship are the electric or other suitable motors M1 and M2, motor M1 being located near the bow of the ship and motor M2 being located near the stern. Said motors are operatively connected by suitable gearing with the drums 21 and 22. Motor M1 drives drum 21 and motor M2 drives drum 22.

Motors M1 and M2 furnish the motive power necessary to move devices or gates D and DD into their extended operative positions and to return the said devices to their inoperative or collapsed positions. Motor M2 is employed to move devices D and DD into their operative positions and motor M1 is employed to return the said devices to their inoperative positions.

Figs. 1 and 2 show the protective devices D and DD in their inoperative position. To move the said devices into their operative positions, motor M2 is started thus driving drum 22. The rotation of said drum 22 causes all four cables 17 to wind up thereon, thus moving the said cables along the opposite sides of hull H towards stern S in the direction shown by the arrows 5 in Figs. 1 and 2 until devices D and DD are in the extended or operative position shown in dotted lines in Fig. 2 and in Figs. 3 and 4. It will be noted from Figs. 2 and 4 that arms 10 are prevented from moving beyond an angle of ninety degrees by the terminal projection stops 14. In the full operative position, arms 10 are perpendicular to the sides of the ship and stops 14 are parallel and abut the sides of the ship. Thus when a torpedo strikes any of the protective devices while in the extended operative position, it will be deflected by the said protective

devices towards the bow B, as shown in dotted lines in Fig. 2.

To return the protecting devices D and DD to their inoperative or collapsed position, motor M1 is started thus driving drum 21. The rotation of said drum 21 causes all four cables 17 to wind up thereon, thus moving the said cables along the opposite sides of hull H, towards bow B, in the direction shown by arrows a in Figs. 1 to 4, until the protecting devices are in the position shown in Figs. 1 and 2, that is until the said protecting devices are in abutting parallel relation to the sides of the ship.

Although there is shown and described herein a preferred embodiment of the invention, it is obvious that numerous changes in details may be made without departing from the spirit or scope of this invention. I have not specified the materials from which the various elements and members of my protecting devices are made, but it is obvious that in view of the primary purpose for which my improved devices are intended, that any strong steel or armor plate would be suitable or desirable.

25 What is claimed is:

1. A protecting device for the hull of a ship arranged on opposite sides of said hull, comprising a plurality of vertical bars secured to said hull, an arm mounted on each of said bars and being movable thereon, a plurality of cables connecting said arms, a plurality of deflector bars secured to said cables intermediate each of said arms, means carried by the ship for moving said cables and arms toward and away from the sides of the ship, at least one of said arms being provided with means to limit the outward movement of said arms from the sides of the ship.

2. A protecting device for the hull of a ship comprising protective units arranged on opposite sides of said hull, each of said units including a plurality of vertical bars secured to said hull, a U-shaped arm movably mounted on each of said bars, a plurality of parallel cables connecting said U-shaped arms, a plurality of deflector bars secured to said cables intermediate each of said U-shaped arms, said deflector bars being parallel to the vertical bars and the U-shaped arms, means carried by one end of the ship for moving said cables and U-shaped arms away from the sides of the ship, means carried by the opposite end of said ship for moving said cables and U-shaped arms towards the sides of the ship, at least one of said U-shaped arms being provided with stop means to limit the outward movement of said U-shaped arms from the sides of the ship.

SAY LOUIS LEE.
